[57] **CLAIM**

I claim the ornamental design for trash receptacle and holder for use in an over-the-road truck, as shown and described.

DESCRIPTION

FIG. 1 is a perspective view of a trash receptacle and holder for use in an over-the-road truck showing my new design, shown in use;

FIG. 2 is a perspective view thereof;

FIG. 3 is a top plan view of the receptacle;

FIG. 4 is a bottom plan view of the receptacle;

FIG. 5 is a front elevational view thereof shown in the direction of line 5—5 of FIG. 3;

FIG. 6 is a side elevational view thereof, shown in the direction of line 6—6 of FIG. 3;

FIG. 7 is another side elevational view thereof, shown in the direction of line 7—7 of FIG. 3; and,

FIG. 8 shows the attachment to a wall portion with the receptacle shown fragmented for ease of illustration.

The broken line showing is for illustrative purposes only and forms no part of the claimed design.
